UNITED STATES PATENT OFFICE.

EDGAR WENGER AND CHARLES E. RODIN, OF CALGARY, ALBERTA, CANADA.

AIR PUMP.

Application filed March 25, 1921. Serial No. 455,580.

To all whom it may concern:

Be it known that we, EDGAR WENGER and CHARLES E. RODIN, citizens of the Dominion of Canada, residing at Calgary, in the county of Calgary and Province of Alberta, Canada, have invented certain new and useful Improvements in Air Pumps, of which the following is a specification.

The present invention relates to air pumps for the inflating of pneumatic tires for automobiles and the principal object is to provide a device of the character described adapted for connection to a cylinder head of an automobile engine, and may be actuated thereby.

Another object is to provide an air pump which will eliminate the passage of gas and oil from the cylinder head into the pneumatic tire.

With these and other objects in view, the invention consists in construction, combination and arrangement of parts as will be hereinafter fully described, illustrated in the accompanying drawing, and pointed out in the claims hereunto appended.

The drawing is a transverse vertical section of the improved air pump.

The air pump illustrated in the drawing is of simple construction and comprises a cylinder member 1 hereinafter designated as the power cylinder.

Underneath the base of the power cylinder is disposed a downwardly extended flanged member 2, the interior of said member being threaded to receive exteriorly threaded tubular nipple 3. The lower portion of the nipple is exteriorly threaded to engage in the threaded aperture a spark plug opening in the cylinder head.

Immediately above the power cylinder 1 is disposed a compression cylinder 4, having its lower extremity 5 outwardly flanged, the face of the flange being threadedly engaged in the upper extremity 6 of the power cylinder.

Centrally disposed in the cylinders is piston rod 7 on which pistons 8 and 9 are fixedly mounted. Pistons 8 and 9 are provided with piston rings 10, 11 and 12. On the lower extremity of piston rod 7 is slidably mounted washer 13 which is held thereon by nut 14.

A seat 30 is provided for washer 13 in the base of the power cylinder 1.

At the conjunction of cylinders 1 and 4, a seat 15 is provided to hold washer 16 in normal position. Immediately above washer

16 is a leather washer 17 which is held rigidly by washer 18. The flange 5 holds washers 16, 17 and 18 in fixed position. Washer 17 has its central portion 19 upwardly disposed and tensioned against piston rod 7 by coil spring 20.

On the upper extremity of cylinder 4 an outwardly flanged member 21 is formed. Threadedly mounted on flanged member 21 is nipple 22 which is provided with tubular member 23. The members 21 and nipple have an exit opening therethrough. A discharge, one-way check valve 24 is centrally disposed in the opening in member 21, whereby air can be discharged into the tubular member 23.

At the apex of piston rod 7 is disposed another check valve 26 provided with inlet ports 27. Inlet valve ports 28 and 29 are provided in cylinder 4. Lubricating members 31 and 32 are disposed beneath intake valve ports 28 and 29.

Air relief ports 33 and 34 are provided in the upper extremity of power cylinder 1.

In use, one of the spark plugs is removed and the pump engaged in aperture for the spark plug in the cylinder head.

Upon actuation of the engine, a mixture of air, gas, and oil is forced through tubular nipple 3 into power cylinder 1. The force drives piston 8 upwardly. Upon this upward movement air is sucked in through the intake valve ports 28 and 29, filling lower portion of cylinder 4. At the same time, the air in the upper portion of the cylinder 4 is forced through check valve 24 and the air passes through tubular member 23, thus inflating tire.

The air which may be in the upper portion of power cylinder 1 will escape through relief ports 33 and 34.

Upon the downward stroke of the pistons, the air in the lower portion of cylinder 4 enters ports 27 and passes through check valve 26 into the upper portion of cylinder 4 above the piston 9. On this stroke, discharge valve 24 automatically closes preventing return of air from tire. Washer 13 enters seat 13^a preventing escape of mixture and giving cushioned action to piston rod, preventing violent vibration.

A safety valve may be provided in any suitable manner (not shown) to release at any desired pressure, thus eliminating the danger of over inflating the tire.

The reciprocating motion of piston rod 7

might have a tendency to allow the passage of the mixture around washer 18 from cylinder to tire but is curtailed by tension of coil spring 20.

5 From the foregoing, it is thought that the construction of our invention will be clearly understood, and, therefore, a more extended explanation has been omitted.

What we claim as new is:

- 10 1. Means for utilizing the actuation of an automobile engine for the inflating of pneumatic tires comprising in combination, a power cylinder, a compression cylinder located at its upper extremity, a reciprocable member centrally disposed in said cylinders, means for actuating said reciprocable member, lubricating members disposed in the wall of compression cylinder, means for transporting the compressed air for the 15 compressing cylinder to the pneumatic tube, a washer member slidable on the lower end of said reciprocable member, and means for fixedly mounting the combination to the cylinder head of an automobile engine.
- 20 2. Means for utilizing the actuation of an automobile engine for the inflating of pneumatic tires comprising in combination a power cylinder, a compression cylinder located at its upper extremity, a plunger rod 25 centrally disposed in said cylinders, a piston fixably mounted near the lower extremity of the plunger rod, a smaller piston fixedly mounted on the apex of said plunger rod, piston rings adjusted to said pistons, a slidable washer member mounted on the lower 30
- 35

portion of the plunger rod, a nut screw-threaded on the end of said plunger rod, and a seat disposed in the base of the power cylinder for the reception of the said slidable washer.

3. Means for utilizing the actuation of an automobile engine for the inflating of pneumatic tires comprising in combination a power cylinder, a compression cylinder located at its upper extremity, a plunger rod 40 centrally disposed in said cylinder, pistons fixedly mounted on said plunger rod, washer members disposed at the conjunction of the cylinders, a washer member disposed between said washer members having a 45 flanged member upwardly disposed, means for tensioning said flanged member against plunger rod, an intake port disposed in the upper portion of the said plunger rod, a check valve centrally disposed above said 50 intake port, intake ports disposed in the compression cylinder, air outlet ports disposed in the power cylinder, a discharge check valve disposed at the extremity of the compression cylinder and adjustable means 55 to release the compressed air from the compression cylinder.

In testimony whereof we hereunto affix our signatures in the presence of two witnesses.

EDGAR WENGER.
CHARLES E. RODIN.
